UNITED STATES PATENT OFFICE.

GEORGE W. REDEKER, OF WHEELING, WEST VIRGINIA.

BALL-COCK-SEAT DRESSER-GUIDE.

1,073,362.

Specification of Letters Patent. Patented Sept. 16, 1913.

Application filed June 10, 1912. Serial No. 702,848.

To all whom it may concern:

Be it known that I, GEORGE W. REDEKER, a citizen of the United States, residing at Wheeling, in the county of Ohio and State 5 of West Virginia, have invented certain new and useful Improvements in Ball-Cock-Seat Dresser-Guides; and I do declare the following to be a full, clear, and exact description of the invention, such as will enable others 10 skilled in the art to which it appertains to make and use the same.

This invention relates to improvements in ball cock seat dresser guides.

One object of the invention is to provide 15 a dresser guide by means of which the seats of ball cocks or float operated valves having bodies without threads, may be readily dressed without placing the same in a lathe.

Another object of the invention is to provide 20 a dresser guide which is adjustable to several sizes and is adapted to be used in connection with a bib seat dresser for the purpose of dressing the seat of a ball cock or closet valve.

25 With these and other objects in view, the invention consists of certain novel features of construction, and the combination and arrangement of parts as will be more fully described and claimed.

30 In the accompanying drawings; Figure 1 is a central vertical sectional view of a ball cock casing showing the invention applied thereto; Fig. 2 is partly a side view and partly a vertical sectional view of the dresser 35 and the guide, showing the manner in which part of the sections of the same are removed to reduce the guide to its proper size to fit the valve casing to which the dresser is to be applied. Fig. 3 is a side view of the 40 dresser. Fig. 4 is a sectional perspective view of one of the sections of the guide.

Referring more particularly to the drawings 45 1 denotes the body or casing of a ball cock or float valve of the usual form where- in the body is smooth or has no screw threads and 2 denotes the valve seat.

50 My improved dresser guide comprises a plurality of cylindrical tubes or shells 3 graduated in size and nested together or fitting one within the other whereby one or more of the same may be removed to adjust the guide to the body or casing of the valve. On the upper ends of the tubes or shells of the guide are annular radially and out- 55 wardly projecting flanges 4, which hold the tubes in place when in use. As clearly shown

the tubes 3 are of an equal length whereby when the annular outwardly projecting shoulders of the same are in contact, the outer or larger tube will project beyond the inner surface of the valve casing 1, whereby when it is desired to remove the tool the dresser head 7 is brought in contact with the projecting lower edge of said outer tube and the tool together with the sleeve thereon readily removed from the valve. The annular flanges of the sleeve also provide efficient means for separating the same by inserting a suitable tool between said flanges. Revolv- 60 65 70 75 80 85 90 95 100 105 110

ably engaged with the innermost tube or shell 3 is the stem 5 of the valve seat dresser 6. The stem 5 has arranged on its inner end a bur or valve dressing bit 7 and on the outer end an operating knob or head 8.

In applying the device, the outer tubes or shells 3 of the guide are removed until the latter is of the proper size to fit within the valve body or casing with which the guide is to be engaged for guiding and holding the dresser while being operated in the usual manner for dressing the valve seat.

Unless the body of a valve is threaded it has heretofore been impossible to dress the valve seat of a ball cock without the same being chucked in a lathe. By providing my improved guide and substituting the same for the usual threaded bonnet of a bib dresser the valve seat may be accurately dressed.

From the foregoing description taken in connection with the accompanying drawings, the construction and operation of the invention will be readily understood without requiring a more extended explanation.

Having thus described my invention, what I claim is;

A ball cock seat dresser guide comprising a plurality of similarly constructed cylindrical tubes of uniform thickness throughout their entire length, graduated in size and telescopically connected, said tubes having smooth inner and outer surfaces arranged to slide freely within each other, radially projecting annular flanges formed on the outer ends of said tubes, whereby they are supported on each other and one or more may be readily removed to adjust the device to the proper size for engagement with a ball cock, the lower edge of the outer or larger tube projecting beyond the inner surface of the valve casing, a dresser stem slidably and revolvably arranged in the smaller tube, and

a dressing bit detachably secured to the lower end of the stem and adapted to be brought in contact with the lower projecting edge of the larger tube when it is desired to remove the tool from the valve casting.

In testimony whereof I have hereunto set

my hand in presence of two subscribing witnesses.

GEORGE W. REDEKER.
